ABSTRACT

A timer switch including a plurality of separately depressible push button switches each electrically connected to a different RC timing circuit. Each timing circuit is connected in electrical parallel to an electrically energizable solenoid operatively attached to a release bar for releasing a depressed push button upon energization of the solenoid through the timing circuit associated with the depressed button.

TIMER SWITCH APPARATUS

This is a continuation of application Ser. No. 252,212, filed May 11, 1972.

BACKGROUND OF THE INVENTION

1. Field of the Invention:

The present invention pertains to timer switch apparatus of the type having a plurality of depressible push button switches.

2. Cross Reference to Related Patents:

See my U.S. Pat. No. 3,325,609 entitled "Timer Switch Controlled By Push Button and Motor Operated Cams" which issued on June 13, 1967.

3. Background of the Prior Art:

Timer switches of the type having a plurality of depressible push buttons each automatically releaseable after a different pre-determined time period find numerous applications. For example, such timer switches are commonly utilized in conjunction with microwave ovens to provide "ON" or "HEAT" periods of various lengths. It is highly desirable, of course, that these switches are readily settable for various pre-determined time periods and are also relatively accurate.

Prior to the timer switch apparatus disclosed and claimed in my above-mentioned U.S. Pat. No. 3,325,609, timer switches were either extremely complicated in design or relatively inaccurate. To provide simplicity of design yet relatively high accuracy, my previous timer switch utilized a plurality of depressible push buttons each individually releaseable by means of a release bar operatively connected to a plurality of adjustable motor driven cams. The cams were relatively easily adjustable so as to allow variations in the length of the actuated period associated with each of the push buttons. Additionally, the locking arrangement provided to retain each of the push buttons in a depressed position was reliable over extended periods of utilization. However, the construction of this apparatus still necessitated considerably higher manufacturing costs than desired as the overall reliability of the apparatus was dependent upon the quality of the motor, cams, and other components utilized to release the depressed push button at the desired moment.

SUMMARY OF THE INVENTION

The present invention represents an improvement on the timer switch apparatus disclosed and claimed in my prior U.S. Pat. No. 3,325,609. Broadly speaking, the present invention replaces the mechanical timing mechanism of my previous invention with electronic timing means operating in conjunction with electrically energizable solenoid means to release a depressed push button switch after a pre-determined period of time.

More specifically, the present invention provides a plurality of electrical timing circuits (e.g. RC timing circuits) each associated with a different push button switch and each connected in electrical parallel to an electrically energizable solenoid. The solenoid is in turn operatively connected to releasable latch means for separately securing the push buttons in a depressed or actuated position. Upon energization of the solenoid through one of the timing circuits, the releasable latch is moved between its push button securing position to a push button release position thereby opening the switch connected to the energizing timing circuit.

As will become readily apparent from a reading of the Detailed Description which follows, the present invention considerably simplifies the commercially available timer switch apparatus and, as a result, significantly reduces manufacturing costs. Further, the length of time which each push button is retained in its depressed position can be readily varied (e.g. simply by changing the resistance in the associated RC timing circuit). This significantly increases the flexibility of the switching apparatus. In addition to the increased flexibility, the present apparatus has demonstrated greater reliability and repeatability than the presently available timer switches. Finally, in the preferred embodiment the movement of a push button release bar is also utilized to sound an alarm bell thereby providing an audible indication that a depressed switch has been released and the "ON" period of the switching apparatus has terminated. This eliminates the need for additional electrical circuitry to provide an audible or visual alarm.

BRIEF DESCRIPTION OF THE DRAWINGS

Referring now to the drawings wherein like numerals represent like elements of the invention throughout the various figures:

FIG. 1 is a view in top plan of the timer switch apparatus provided by the present invention;

FIG. 2 is an enlarged sectional view as seen from the line 2-2 in FIG. 1, parts thereof being broken away;

FIG. 3 is a sectional view as seen from the line 3-3 in FIG. 2, parts thereof being broken away;

FIG. 4 is a view in perspective of the contact carriage forming part of each depressible push button utilized in the present invention;

FIG. 5 is a view in perspective of the sliding element of each depressible push button;

FIG. 6 is a perspective view of the release bar for latching and releasing the depressed push button; and

FIG. 7 is an electrical schematic of the circuitry utilized to time the release of a depressed push button.

DETAILED DESCRIPTION OF THE PREFERRED EMBODIMENT

In the drawings, the numeral 10 generally designates the timer switch apparatus provided by the present invention. Switch apparatus 10 includes a plurality of generally identical push button switches 12a-12f which are mounted in juxtaposition in a generally U-shaped base member 14. As shown, base member 14 includes an essentially solid outer or front wall 15 and a rear wall formed by a plurality of spaced fingers or upright projections 16. Base member 14 is attached to a chassis 17 by suitable means.

Since switches 12a-12f are generally identical, only a single switch (e.g. switch 12a) need be described in detail. Switch 12a includes a cube-shaped button or knob 18 which is attached to a slideable shaft 20. Shaft 20 extends through a slot in the front wall 15 of U-shaped member 14 and between two adjacent ones of the fingers 16 forming the rear wall. A compression spring 22 in engagement with front wall 15 of U-shaped member 14 biases switch 12a outwardly to a non-depressed position. A contact carriage 24 is fixedly attached to the slideable shaft 20 by suitable means (not shown) for movement between the front and rear walls

of member 14. The contact carriage 24 is formed from a suitable non-conducting material such as various plastics. A pair of spring biased contact elements 25a and 25b are carried by contact carriage 24 in an axially spaced relationship. Contact element 25a is slidably engageable with a grouping of three spatially separated stationary contact elements 26a, 26b, and 26c. Similarly, contact element 25b is slidably engageable with stationary contacts 27a, 27b and 27c. Push buttons 12b-12f are provided with similar carriages and contact elements with the exception of push button 12f which includes a third sliding contact 25c mounted on carriage 24 for contacting a grouping of stationary contact elements 28a, 28b and 28c. As explained subsequently in greater detail, contact element 25a engages the outer two contact elements 26a and 26b in its non-depressed position and engages the inner two contact elements 26b and 26c when pushed inwardly against the bias of spring 22 to its depressed position. Similarly, sliding contact 25b engages contact elements 27a and 26b in its non-depressed position and contact elements 27b and 27c in its depressed position. Contact elements 26a-26c, 27a-27c and 28a-28c are mounted on a terminal or printed circuit board 29 which is attached to chassis 17.

Releaseable switch latching means in the form of an elongated release bar 30, best seen in FIG. 6, having a plurality of similar slots 32 axially spaced therealong. A plurality of upstanding shoulder portions 34 are positioned along the front edge of the release bar 30 adjacent a corner of each of the slots 32. Each elongated slot 32 is of sufficient size so as to receive a different one of the fingers 16 forming the rear wall of U-shaped member 14. The fingers 16 project through the slots 32 so as to allow limited axial movement of the release bar 30 while substantially preventing movement of bar 30 in the same direction as the movement of switches 12a-12f. With release bar 30 so positioned, each of the shoulders 34 is positioned adjacent a different one of the slideable shafts 20 of switches 12a-12f for the purpose subsequently described.

The slideable shaft 20 of switch 12a includes an offset or elevated outer portion 20a. A finger portion 35 extends inwardly from outer shaft portion 20a into an elongated opening 36 in shaft 20. An outer end of compression spring 22 is coiled about finger portion 35 so as to urge button 12a outwardly as previously described.

Slideable shaft 20 further includes a rectangular opening 38 in the innermost end thereof. A tooth-shaped member 40 projects into the opening 38 and is positioned with respect to the adjacent shoulder 34 of release bar 30 so that the shoulder is moved axially in a direction away from the member 40 as push button 12a is depressed. Upon the outermost extended point of tooth 40 passing shoulder 34, the release bar 30 then moves toward the tooth 40 positioning the shoulder 34 in the groove defined by the tooth-shaped member 40. This prevents the slideable shaft 20 from returning to its forward or non-depressed position upon the urging of compression spring 22. It should be noted that if one of the remaining switches 12b-12f is now depressed (e.g. switch 12f as shown depressed in FIG. 3), the tooth shaped member 40 of the newly depressed switch will cam the release bar 30 away from tooth 40 of depressed switch 12a thereby releasing the slideable shaft

20 of switch 12a as the depressed one of the other switches 12b-12f is latched.

It should be additionally noted that, if desirable, apparatus can be utilized in conjunction with switches 12a-12f to prevent more than one switch from being simultaneously depressed. For a description of one particularly preferred form of such apparatus, see my U.S. Pat. No. 3,325,609.

An electrically energizeable solenoid 50 is mounted 10 on chassis 17 and includes a plunger element 51 which is attached to an end of release bar 30 by a pin 52. When solenoid 50 is in a non-energized state, plunger element 51 is urged outwardly by spring means within apparatus 10 (not shown) and, consequently, release bar 30 is normally biased in a direction away from solenoid 50. This results in tooth shaped member 40 of the depressed one of the switches 12a-12e (e.g. switch 12a) engaging a shoulder 34 of release bar 30 preventing the depressed switch from returning to its non-depressed position. 15 When solenoid 50 is energized, plunger 51 is drawn inwardly causing release bar 30 to move longitudinally toward solenoid 50. As this occurs, shoulder 34 is freed from the tooth shaped member 40 releasing depressed switch 12a to return to its non-depressed position. 20 As shown, the end of release bar 30 opposite the end attached to solenoid 50 includes an upturned portion 30a which is suitable for contacting a bell 55 mounted on chassis 17. Upon energization of solenoid 50, the upturned portion 30a of release bar 30 is moved 25 toward bell 55 contacting the lip thereof so as to provide an audible indication that depressed switch 12a has been released. Switches 12b-12f are similarly latched by bar 30 and released upon energization of solenoid 50.

30 Turning now to FIG. 7, the electrical timing circuitry for energizing solenoid 50 and releasing the depressed one of the switches 12a-12f is illustrated. A pair of terminals 60 and 61 are suitable for connecting to a 115 volt AC power source (not shown); terminal 60 being positive and terminal 61 being neutral or ground. A lead 62 is connected to terminal 60 and through a neon bulb 64 to terminal 26a of switch 12f. When switches 12a-12f are in their de-energized position as schematically shown in solid lines in FIG. 7, terminal 26a of switch 12f is connected to terminal 26a of each of the switches 12a-12f by contact element 25a extending between stationary contacts 26a and 26b of each of the switches and a plurality of leads 65 connecting each of the terminals 26b of switches 12a-12f to the terminal 50 26a of an adjacent one of the switches. A lead 68 connects stationary contact 26b of switch 12a to terminal 61 and, thus, when the switches 12a-12f are all in their de-energized position, a circuit is completed between terminals 60 and 61 through neon bulb 64. This lights bulb 64 providing a visual indication that the apparatus is in its "ready" state; i.e., that one of the switches 12a-12f can be depressed to provide current to the switched load in the manner subsequently described.

55 A lead 70 is connected to terminal 60 and through a capacitor 72, a diode 73 and a resistor 74 to terminal 26c of switch 12a. A lead 79 connects the contact element 26c of each of the remaining switches 12b-12f to contact 26c of switch 12a. An output terminal 75 suitable for connecting to a switched load (e.g. a relay which energizes a voltage supply to provide power to a microwave oven), is also connected to terminal 26c through a lead 76. A neon bulb 77 is connected to lead

76 and to lead 62 through a lead 78 to provide a visual indication of a completed circuit to the switched load (i.e., to indicate that switching apparatus 10 is in its "OPERATE" mode).

A lead 80 is connected to lead 70 between capacitor 72 and diode 73. Lead 80 is connected through a resistor 82 to a lead 83 which, in turn, connects each of the terminals 27c of switches 12a-12f in parallel to one another through resistors 85-90, respectively. As will subsequently be made apparent, each of the resistors 85-90 form the variable resistance portion of an RC timing circuit for determining the length of time which the associated one of the switches 12a-12f remains depressed. Preferably, resistors 85-90 are readily removable from the circuit so as to allow easy substitution thereof for varying the RC timing periods. In FIG. 1, it can be seen that resistors 85-90 are each slideably removable from a pair of female terminals or receptacles mounted on printed circuit board 29.

Lead 83 and resistors 85-90 are also connected to AC terminal 61 through an SCR 91 and a Zener diode 92. As shown, the anode 93 of SCR 91 is connected to a lead 94 and terminal 61 whereas the SCR cathode 95 is connected to a lead 96 which is in turn connected to a lead 97 and the anode of the Zener diode 92. The lead 97 is connected to lead 80 between resistor 82 and common lead 83 through diode 92. A terminal 98 of lead 97 is connectable to the switched load for external supply (i.e., AC neutral or ground) for allowing energization of solenoid 50, shown connected between leads 70 and 97, and thus terminate the energizing power supplied to the load upon the occurrence of a certain event (e.g. the opening of the door of a microwave oven). Capacitor 72, diode 73 and resistor 74 comprise a constant current supply for stabilizing the voltage at Zener diode 92 reducing the effect of line variations.

As shown, terminal 28a of switch 12f is connected through a lead 100 to a potentiometer 102 in a lead 104. The potentiometer 102 is connected through a resistor 105 to lead 97 and through a resistor 106 and common charging capacitor 108 to a lead 110. A resistor 112 is connected in parallel to resistors 102 and 105. Resistors 105 and 106 provide the proper biasing voltage levels at a transistor 118 subsequently described. Resistors 102, and 112 function as trimmer resistors to compensate for variations in component and power levels in the RC timing circuit.

The terminal 28b of switch 12f is connected to the base 120 of PNP transistor 118 through a lead 121. The emitter 122 of transistor 118 is connected through a lead 123 to the terminal 27b of switch 12f. As shown, terminal 27b of switch 12f is connected in series to the terminals 27b of switches 12a-12e by a lead 124. Finally, the collector 126 of transistor 120 is connected to lead 110 and through a neon bulb 130 and a resistor 132 to the gate 135 of SCR 91. A resistor 138 is connected between gate 135 and cathode 95 of SCR 91 to prevent the occurrence of transient voltage spikes in the timing circuit. Finally, a lead 140 connects lead 96 to lead 104 between resistor 106 and capacitor 108.

Typical examples of component values for use in a timing circuit to energize solenoid 50 utilizing a 115 volt AC power source are as follows:

COMPONENT	VALUE
Resistor 74	100 Ohms
82	4700
85	
86	Selection variable,
87	approximately 10,000
88	Ohms per each timing
89	second desired.
90	
102	1000
	(potentiometer)
105	1800
106	12000
112	1000
132	100
138	470
Capacitor 72	4.0-4.7 MFD
108	5.0
Diode	IN5060
SCR	S2001MS2
Zener Diode	IN4763
Transistor	2N5400
Neon Bulb 130	5AHB

The operation of the preferred timing circuitry can be explained as follows. With 115 volts AC applied across terminals 60 and 61 and switches 12a-12f in their de-energized position (i.e., non-depressed position) neon bulb 64 is caused to glow in the manner previously described. Upon depression of one of the switches 12a-12f (e.g. switch 12a) current flow through neon bulb 64 is terminated and the switchable load connected to terminal 75 is switched on by the connection of terminal 75 to terminal 61 through switch 12a. This also results in the lighting of neon bulb 77 in the manner previously described.

Upon depression of switch 12a, sliding contact 25b engages terminals 27b and 27c so as to provide a current path therethrough connecting AC terminal 60 to the emitter 122 of PNP transistor 120. This raises the potential of emitter 122 relative to base 120 switching PNP transistor 118 into its conducting state. Upon this occurring, the current flow through lead 110 charges capacitor 108 through resistors 102, 105, 106, 112 and through resistor 85 connected to depressed switch 12a. Capacitor 108 continues to charge at a rate determined by the resistance of resistor 85 until it reaches the firing potential of neon bulb 130 at which time bulb 130 fires through the solenoid 50 energizing the solenoid.

Upon energization of solenoid 50, the release bar 30 is pulled toward solenoid 50 causing the shoulder 34 to be released from the tooth shaped member 40 of switch 12a. This allows the switch 12a to return to its non-depressed position upon the urging of compression spring 22. Upon switch 12a returning to its non-depressed position, the load is switched to an "off" state and the apparatus is again "ready" for another cycle of operation. It should be understood that a different timing period is associated with each of the push buttons 12a-12f due to the difference in the resistances of resistors 85-90, and thus the charging rate of capacitor 108.

Since my invention has been described in particular detail with respect to only a single preferred embodiment thereof, numerous modifications thereto will be readily apparent to the artisan. For instance, without requiring any inventive skill the polarity of the described timing circuit can be reversed. Additionally, one of the push button switches 12a-12f can have asso-

ciated therewith a variable resistance to allow analog selection of the desired RC timing period (e.g. resistor 90 of switch 12f as shown in dotted lines in FIG. 7). It is my intent to be limited solely by the spirit and scope of the appended claims.

What is claimed is:

1. Timer switch apparatus comprising:

- a. a plurality of push button switches each movable between a depressed operative position and a non-depressed position;
- b. releasable switch latching means including an elongated release bar positioned generally perpendicular to the movement of said push button switches and movable longitudinally between two limits of movement, said switch latching means having means for retaining each of said push button switches in its depressed position at a position of said bar and said switch latching means releasing a depressed push button switch upon movement of said bar a predetermined distance away from said position and toward one of said limits;
- c. electrically energizable solenoid means mechanically connected to said release bar for longitudinally moving said bar said predetermined distance upon energization of said solenoid means whereby to release a depressed push button switch;
- d. electrical timing means electrically connected to said solenoid means and including a plurality of electrical timing circuits, each circuit being electrically connected to a different one of a plurality of said push button switches for energizing said solenoid means and releasing a depressed push button switch after the passage of a predetermined amount of time; and
- e. electrical control means connected to said solenoid means independent of said timing means for releasing a depressed push button switch upon the occurrence of an event other than the passage of predetermined amount of time.

2. The timer switch apparatus of claim 1 including a bell-like device wherein said release bar includes a por-

tion thereof for engaging said bell-like device upon the energization of said solenoid means so as to provide an audible indication of the release of a depressed one of said push button switches.

3. Timer switch apparatus comprising:

- a. a plurality of push button switches each movable between a depressed operative position and a non-depressed position;
- b. releasable switch latching means including an elongated release bar positioned generally perpendicular to the movement of said push button switches and movable longitudinally between two limits of movement, said switch latching means having means for retaining each of said push button switches in its depressed position at a position of said bar and said switch latching means releasing a depressed push button switch upon movement of said bar a predetermined distance away from said position and toward one of said limits;
- c. electrically energizable solenoid means mechanically connected to said release bar for longitudinally moving said bar in one direction of movement upon energization of said solenoid means;
- d. means moving said latch bar in its other direction of movement upon deenergization of said solenoid means;
- e. electrical timing means electrically connected to said solenoid means and including a plurality of electrical timing circuits, each circuit being electrically connected to a different one of a plurality of said push button switches for changing the energization of said solenoid means to release a depressed push button switch after the passage of a predetermined amount of time; and
- f. electrical control means connected to said solenoid means independent of said timing means for releasing a depressed push button switch upon the occurrence of an event other than the passage of predetermined amount of time.
